UNITED STATES PATENT OFFICE

106,988

DESIGN FOR A SACHET

Isidore Perlmutter, New York, N. Y.

Application October 8, 1937, Serial No. 72,073

Term of patent 7 years

To all whom it may concern:

Be it known that I, Isidore Perlmutter, a citizen of the United States and a resident of New York, in the county of New York and State of New York, have invented the new, original, and ornamental Design for a Sachet, of which the following is a specification, reference being had to the accompanying drawing forming a part thereof.

Fig. 1 is a top perspective view of a sachet showing my new design.

Fig. 2 is a side elevational view thereof.

I claim:

The ornamental design for a sachet, as shown.

ISIDORE PERLMUTTER.
